O. N. Butler
Attorney.

UNITED STATES PATENT OFFICE.

GERALD D. GROSNER, OF WEST CHESTER, PENNSYLVANIA, ASSIGNOR TO SHARPLES SPECIALTY COMPANY, OF WEST CHESTER, PENNSYLVANIA, A CORPORATION OF PENNSYLVANIA.

CENTRIFUGAL MACHINE.

1,302,031.

Specification of Letters Patent. Patented Apr. 29, 1919.

Application filed November 28, 1917. Serial No. 204,338.

To all whom it may concern:

Be it known that I, GERALD D. GROSNER, a citizen of the United States, residing at West Chester, in the county of Chester and 5 State of Pennsylvania, have invented certain Improvements in Centrifugal Machines, of which the following is a specification.

My invention relates to improved means 10 designed more particularly for checking the revolutions of the bowls of centrifugal machines, and it is characterized by the adaptability of a simple construction to simultaneously checking and steadyng or maintaining in correct position a device revoluble at 15 high speed and liable to eccentric action.

In the accompanying drawings, Figure 1 is a sectional elevation of a centrifugal machine having my improvements applied thereto; Fig. 2 is a sectional view taken on 20 the line 2—2 of Fig. 1; and Fig. 3 is a sectional view taken on the line 3—3 of Fig. 2.

The machine illustrated in the drawings, to show an application of my invention, comprises a frame 1, provided with a case 2 25 containing a cylindrical bowl 3 which is suspended and revoluble by a shaft 4, the bottom of the bowl being provided with a boss 5 which revolves and has a limited 30 movement in the bearing 6 connected with the case.

In accordance with my invention, a pair 35 of jaws or clamps 7, curved to conform to the periphery of the bowl 3, are mounted to oscillate in the case 2 by means of their hinges 8, the latter being journaled on parallel pintles or bearings 9 of a yoke 10 having end loops 11 for engagement by bolts 12 fixed to the case.

40 Coiled springs 13 are connected to lugs 14 which are fixed to the clamps 7 adjacent to the hinges and act to press fibrous linings 7' of such clamps against the bowl.

A block 15 is disposed between the clamps 45 7 between the hinges and the bowl, the block having the bifurcations 15' which guide it by embracing the clamps, and a bolt 16 is fixed to the block and extends, between the hinges, through the case. A collar 17 is 50 fixed to the bolt 16 and has trunnions 16' on which are mounted the bifurcations 18'

of a cam 18, the latter being operated by an arm 18'.

In operation, when the cam 18 is in the position shown in Fig. 1, the bolt 16 and 55 the block 15 are held in an inner position permitting the springs 13 to draw the clamps together into frictional contact with the bowl 3, which, when revolving, is checked not only without throwing it off center but 60 while holding it in correct axial position, avoiding wabbling which commonly takes place. The bowl is released by turning the cam 18 past its angle or dead center position, which draws the bolt 16 and block 15, 65 the latter spreading the clamps 7 and holding them out of contact with the bowl 3 against the action of the springs 13. The clamps are adapted to be drawn back against 70 the case 2, and thereby permit, when in such position, the ready insertion and withdrawal of the bowl 3 without interference therewith.

Having described my invention, I claim:

1. The combination with a revoluble suspended bowl, of oscillatory clamps adapted for engaging the periphery of said bowl near its bottom, and means for holding said clamps alternately in and out of engagement with said bowl. 75

2. The combination with a case and a bowl revoluble therein, of hinged devices supported by said case for frictionally engaging said bowl, a bolt adapted to act through said case, means carried by said bolt for disengaging said devices from said bowl, and a cam engaging said bolt and case for operating said means. 85

3. The combination with a revoluble bowl and means for supporting the same, of a 90 pair of clamps having hinges carried by said means, a spring for drawing said clamps together into engagement with said bowl, a reciprocatory device acting between said bowl and hinges for spreading said 95 clamps, and means comprising a cam for operating said device.

4. The combination with supporting means and a yoke having bearings fixed thereto, of oscillatory clamps carried by said bearings, 100 a spring for drawing said clamps together, a block for spreading said clamps, a bolt

fixed to said block and extending through said supporting means and a rocking cam having bifurcations pivotally connected to said bolt and adapted for holding said bolt 5 in different positions.

5. The combination with a case, of a revolute suspended bowl, oscillatory clamps supported within said case for engaging the

periphery of said bowl, means for pressing said clamps against said bowl, and means 10 comprising a lever exterior to said case and a cam for disengaging said clamps from said bowl.

In testimony whereof I have hereunto set my name this 15th day of November, 1917.

GERALD D. GROSNER.
